INVENTOR

Marion A. Tryens

BY

Charles N. Butler

ATTORNEY.

UNITED STATES PATENT OFFICE.

MARION A. TRYENS, OF WEST CHESTER, PENNSYLVANIA.

MUSIC-HOLDER.

1,157,194.

Specification of Letters Patent.

Patented Oct. 19, 1915.

Application filed August 29, 1913, Serial No. 787,247. Renewed April 24, 1915. Serial No. 23,767.

To all whom it may concern:

Be it known that I, MARION A. TRYENS, a citizen of the United States, residing at West Chester, in the county of Chester and State of Pennsylvania, have invented certain Improvements in Music-Holders, of which the following is a specification.

My invention is an improved music holder adapted for general use but more particularly for use by performers who carry their instruments. It is adapted especially for the attachment of music to band or other portable instruments and supports.

The improvements are characterized by the simplicity and efficiency of the mechanism, by which a book is supported from the top and readily opened, closed or detached, while the sheets are readily adjusted and fixed in any desired relation so that any sheet or page can be brought into position for use and securely held without covering part of the music, such sheets being held by convenient connections permitting them to be reversed, clamped and unclamped very readily.

In the accompanying drawings, Figure 1 is a perspective view in illustration of my improved mechanism; Fig. 2 is an elevation in illustration of the mechanism detached from its support; Fig. 3 is a sectional view taken on the line 3-3 of Fig. 2; and Fig. 4 is a sectional view taken on the line 4-4 of Fig. 3.

The mechanism, as illustrated in the drawings, comprises a stem 1, which may be fixed to any instrument or supported in any desired manner, in combination with a rod 2 having a section 2^a which fits in the socket 1^a of the stem.

40 A cross bar 3 is connected with the top of the rod 2 by a swivel comprising a cylindrical stud or pivot 2^b on the top of the rod and a boss 3^a on the cross bar, the boss containing a cylindrical socket 3^b adapted to receive the stud or pivot. The stud 2^b is provided with the cross pin 2^c whose ends are movable in the longitudinal slots 3^c of the boss (for effecting engagement with or disengagement from the stud) and revoluble in the circular channel 3^d of the boss, to permit the cross bar to be revolved on the rod.

50 Split rings or loops 4 pass through the ends of the cross bar 3 and the backs or covers 5 and sheets 6 forming the music

book. These rings provide hinges for the 55 otherwise disconnected parts 5 and 6 which are thereby supported from their tops so that they hang by gravity in the desired planes without buckling or displacement as in the case of side supports. The connections permit the covers 5 and sheets 6 to be readily turned over the cross bar 3, to open or close the book and to bring the desired page before the performer, while the opposite page of a sheet that has been turned 60 over can be brought into position for use or the view of the performer by turning the cross bar with the book thereon about the supporting rod 2 through the action of the 65 swivel.

70 A rectangular sleeve 7 is movable on the rectangular section 2^d of the rod, and laterally extending bearings 7^a are fixed to the sleeve.

Clamping members 8 are provided with 75 bearings 8^a which are journaled on the bearings 7^a. A spring 9, having the coils 9^a on the bearings 7^a, is provided with the extensions 9^b which engage the lower ends of the lever members 8 and act to move their 80 upper ends together. By pressing together the lower arms of the clamping members 8 and properly adjusting the sleeve 7 the jaws or upper ends of such members can be caused to engage the bottoms or lower edges 85 of the covers and sheets of the music book to hold them firmly in any desired relation while preventing the cross bar from turning on its supporting rod, or the sheets and covers can be readily disengaged when 90 it is desired to close or adjust or turn the book, and it will be observed that the jaws of the clamp are adapted for so engaging the sheets that they are firmly held thereby and by the rings against the covers without covering the music.

95 When the music is not required the cross bar with the book thereon is readily detached and can be placed in a pocket of the performer or otherwise protected.

100 Having described my invention, I claim:

1. In a music holder, a rod, means comprising loops for holding separate sheets so that they can be turned to opposite sides of said rod, and clamping means for engaging 105 sheets on opposite sides of said rod.

2. In a music holder, a rod, a cross bar swiveled on said rod, loops carried by said

cross bar and adapted for holding separate sheets so that they can be turned over said cross bar, and a clamp movable on said rod and adapted for simultaneously engaging sheets oppositely disposed with reference to said rod.

In testimony whereof I have hereunto set

my hand this 21st day of August, 1913, in the presence of the subscribing witnesses.

MARION A. TRYENS.
